CLAIM

We claim the ornamental design for a water-resistant, battery-powered speaker for handheld devices, as shown and described.

DESCRIPTION

FIG. 1 is an isometric view of the water-resistant, battery-powered speaker for handheld devices, showing primarily the top, front and left side thereof;

FIG. 2 is an isometric view of the water-resistant, battery-powered speaker for handheld devices, showing primarily the top, front and right side thereof;

FIG. 3 is an isometric view of the water-resistant, battery-powered speaker for handheld devices, showing primarily the bottom, front and left side thereof;

FIG. 4 is an isometric view of the water-resistant, battery-powered speaker for handheld devices, showing primarily the bottom, front and right side thereof;

FIG. 5 is an isometric view of the water-resistant, battery-powered speaker for handheld devices, showing primarily the top, rear and right side thereof;

FIG. 6 is an isometric view of the water-resistant, battery-powered speaker for handheld devices, showing primarily the top, rear and left side thereof;

FIG. 7 is an isometric view of the water-resistant, battery-powered speaker for handheld devices, showing primarily the bottom, rear and right side thereof;

FIG. 8 is an isometric view of the water-resistant, battery-powered speaker for handheld devices, showing primarily the bottom, rear and left side thereof;

FIG. 9 is an isometric view of the water-resistant, battery-powered speaker for handheld devices, showing primarily the bottom and rear thereof;

FIG. 10 is an isometric view of the water-resistant, battery-powered speaker for handheld devices, showing primarily the rear and the top thereof;

FIG. 11 is an isometric view of the water-resistant, battery-powered speaker for handheld devices, showing primarily the top and rear thereof;

FIG. 12 is a right-side elevational view of the water-resistant, battery-powered speaker for handheld devices;

FIG. 13 is a left-side elevational view of the water-resistant, battery-powered speaker for handheld devices;

FIG. 14 is a front elevational view of the water-resistant, battery-powered speaker for handheld devices;

FIG. 15 is a rear elevational view of the water-resistant, battery-powered speaker for handheld devices;

FIG. 16 is a top plan view of the water-resistant, battery-powered speaker for handheld devices; and,

FIG. 17 is a bottom plan view of the water-resistant, battery-powered speaker for handheld devices.

The broken lines shown are included for the purpose of illustrating portions of the water resistant battery powered speaker for handheld devices that form no part of the claim.
